UNITED STATES PATENT OFFICE.

HARRY C. WELCOMER, OF STEELTON, PENNSYLVANIA.

ELECTRICAL WATER HEATER.

Application filed August 25, 1927. Serial No. 215,357.

The object of my said invention is the provision of a peculiar and advantageous electrical heater of the type adapted to be immersed in a body of water or other fluid to be raised in temperature.

The invention in all its details will be fully understood from the following description and claims when the same are read in connection with the drawings accompanying and forming part of this specification, in which:

Figure 1 is a side elevation of the electrical water heater constituting the preferred embodiment of my invention.

15 Figure 2 is a top plan view of the same.

Figure 3 is a horizontal section taken on the plane indicated by the line 3—3 of Figure 1, looking downwardly.

20 Figure 4 is an enlarged vertical section taken on the plane indicated by the line 4—4 of Figure 3.

Figure 5 is a detail vertical section taken on the plane indicated by the line 5—5 of Figure 4.

25 Figure 6 is a diametrical section taken on the plane indicated by the line 6—6 of Figure 2.

Figure 7 is an enlarged vertical section showing the specific construction of the handle portion of my improvement.

30 Figure 8 is a horizontal section taken on the plane indicated by the line 8—8 of Figure 7.

Figure 9 is an enlarged horizontal section taken on the plane indicated by the line 9—9 of Figure 6, looking downwardly and showing the thermometer bracket and the thermometer of my improvement.

35 Figure 10 is a detail perspective of one of the frame members of my improvement.

Figure 11 is a detail perspective of one of the braces.

40 Figures 12 and 13 are illustrative of a slight modification hereinafter specifically referred to.

Similar numerals of reference designate corresponding parts in all the views of the drawings.

45 Among other elements, my improved heater comprises frame members 1 of appropriate metal arranged in a circular series and spaced apart as clearly appears in Figure 1. The said members 1 are identical in construction and therefore a detailed de-

scription of the one illustrated in Figure 10 55 will suffice to impart a definite understanding of all. The frame member alluded to is formed in one piece of appropriate metal and is in strap form with spaced uprights 2 in parallelism, outwardly extending apertured terminals 3 at the upper ends of said uprights, bights 4 at the lower ends of the uprights 2, and a cross bar 5 spaced above the lower ends of the uprights 2 and joining the inner ends of the loops or bights 4. 60 65

In the circular series of frame members 1 and arranged on the cross bars 5 thereof is the annular receptacle 6 of my improvement, the said annular receptacle being also by preference of appropriate metal and being 70 provided at its upper edges of the side walls with lateral flanges 7. It will be noted from Figures 1, 4, 5 and 6 that the loop portions 4 of the frame members 1 extend below the bottom of the receptacle 6 and constitute legs designed to support the bottom of the receptacle 6 in spaced relation to a pan, 75 tub or other receptacle in which a body of water is to be heated.

80 Superposed on the flanges of the receptacle 6 is an annulus 8 of thick metal, the said annulus 8 being designed to lend increased weight to the device so as to hold it down in close proximity to the bottom of a receptacle and being also designed to be 85 heated by the heating unit hereinafter described and to give off heat to the water with which it directly contacts. The terminals 3 of the frame members 1, the flanges of the receptacle 6 and the annulus 8 are connected together by inner and outer bolts 9, and by particular reference to Figure 4 it will be noted that washers 10 are interposed between the terminals 3 and the the receptacle flanges, and that washers 11 are interposed between the terminals 3 and the under side of the annulus 8, the said washers being water proof with a view to excluding water from the interior of the receptacle 6. 90 95

100 Arranged in the receptacle 6 and superposed on the bottom thereof is a dielectric annulus 12, of asbestos or other appropriate material, and also arranged in the receptacle 6 and superposed on the said annulus 12 is the heating unit of my improvement, the said heating unit being made up of a core 13 annular in form, and wiring 14 coiled about the said core 13 in the manner best shown 105

in Figures 3, 4 and 5. It will also be understood that braces 15, preferably of metal and which are good conductors of heat are interposed between and connected to the core 13 and the metallic annulus 8 so that in effect the said annulus 8 is a part of the heating unit of the device.

For the purpose of venting the receptacle 6 I provide a pipe 16 connected to the annulus 8 and in communication with the interior of the receptacle 6 as appears in Figure 6, the said pipe 16 extends upwardly from the annulus 8 to a slight extent and then inwardly to a point in coincidence with the receptacle 6 and then vertically upward, the last named portion of the pipe being designed to form part of the handle through the medium of which the device may be conveniently moved from place to place and disposed in and removed from a receptacle containing water. The terminals of the wiring 14 are designated by 17, Figures 6 and 7, and the said terminals are arranged in an insulating tube 18 and by said tube 18 are electrically isolated from the annulus 8. In this connection it will be observed in Figure 6 that the insulating tube 18 extends through an aperture in the annulus 8 and also extends a slight distance above the annulus 8 and then inwardly to a point in close proximity to the inner upright portion of the pipe 16, and then extends upwardly alongside of and closely adjacent to the inner upright portion of the pipe 16.

Surrounding the inner upright portions of the pipe 16 and the insulating tube 18 is an elastic sleeve 19, preferably of rubber which serves to hold the insulating tube 18 to the inner upright portion of the pipe 16 and at the same time constitutes a convenient hand grasp for the movement of the heating device.

Within the purview of my invention the terminals 17 may be extended to and connected with any appropriate source of electric energy, and in this connection I would have it understood that when deemed expedient the terminal 17 may comprise fuses 17^x, Figure 7, the said fuses 17^x when employed being conveniently arranged in a casing 25 connected to and carried by the inner upright portion of the pipe 16. The said fuses 17^x are designed to prevent injury to any portion of my improved device in the event of mishap, but I would have it understood that without departing from my invention the fuses 17^x may be altogether omitted.

Straddling and frictionally maintained in position on the inner upright portion of the pipe 16 is the thermometer bracket 26 of my improvement, the said bracket 26 being adjustable vertically on the said portion of the pipe 16. Carried on the bracket 26 which

extends laterally relative to the inner upright portion of the pipe 16 is a thermometer 27 which is readily readable by a person looking down into the water in which my novel heater is immersed.

Manifestly the thermometer 27 arranged as indicated will enable a person to readily determine when the temperature of the water has been raised to the extent desired, and therefore the thermometer constitutes a convenient adjunct to my improvement.

It will be appreciated from the foregoing that the heated portion of my improvement is annular in form and is therefore calculated to offer a large heating surface in direct contact with the water to be heated which is manifestly an important advantage. It will also be appreciated that by virtue of its general annular form my novel heater is light in weight and may be therefore manipulated from place to place with but little effort.

When deemed expedient, the terminals 17 of the wiring 14 may be connected with a plug, not shown, designed to be placed in an outlet receptacle with a view to electrically connecting my novel device with conventional or any other suitable house wiring. The said plug, however, is not per se of my invention and therefor I have deemed it unnecessary to illustrate the same.

I have entered into a detailed description of the construction and relative arrangement of the parts embraced in the present and preferred embodiment of my invention in order to impart a full, clear, and exact understanding of the said embodiment. I do not desire, however, to be understood as limiting myself to the construction shown and described, my invention being defined by my appended claims within the scope of which modifications may be made without departure from my invention. For instance, within the purview of my invention, the heating element 14 may be arranged vertically about the core 13, Figure 13, and the heating element 14 may be made in sections or side units, Figure 12, so that in case one section or side unit should break the other section or side unit will continue to serve.

Having thus described the invention, what I claim as new and desire to secure by Letters Patent is:

1. An electrical heater comprising a series of spaced frame members of general U-shape, each of said members having upright spaced portions and a cross bar disposed above the lower ends of said upright portions and also having outwardly extending apertured terminals at the upper ends of said upright portions, an annular receptacle arranged in said frame members and on the cross bars thereof and having flanges superposed on said apertured terminals, an annulus superposed on the flanges of the recep-

- tacle, means connecting the said terminal portions, flanges and annulus together, means for excluding water from the interior of the receptacle, a dielectric annulus arranged in the annular receptacle and superposed on the bottom thereof, and a heating unit disposed on said dielectric annulus and having terminals carried through an aperture in the first named annulus. 50
- 5 2. An electrical heater comprising a series of spaced frame members of general U-shape, each of said members having upright spaced portions and a cross bar disposed above the lower ends of said upright portions and also having outwardly extending apertured terminals at the upper ends of said upright portions, an annular receptacle arranged in said frame members and on the cross bars thereof and having flanges superposed on said apertured terminals, an annulus superposed on the flanges of the receptacle, means connecting the said terminal portions, flanges and annulus together, means for excluding water from the interior 55 of the receptacle, a dielectric annulus arranged in the annular receptacle and superposed on the bottom thereof, and a heating unit disposed on said dielectric annulus and having terminals carried through an aperture in the first named annulus, the said heating unit including a core and conductive braces interposed between and connecting said core and said annulus and arranged in the receptacle. 60
- 10 3. An electrical water heater comprising an annulus having a receptacle, a heating unit arranged in said receptacle and having wiring terminal extending outside the receptacle, a pipe connected with the interior of the receptacle and having an inwardly extending portion and an upright portion, the latter adjacent to the center of the annulus, an insulating tube containing the wiring terminals and connected with the annulus and having an inwardly extending portion exterior of the annulus and also having an upright portion arranged closely adjacent the upright portion of the pipe and an elastic sleeve embracing the upright portions 65
- 15 4. An electrical water heater comprising an annulus having a receptacle, a heating unit arranged in said receptacle and having wiring terminals extending outside the receptacle, a pipe connected with the interior of the receptacle and having an inwardly extending portion and an upright portion, the latter adjacent to the center of the annulus, an insulating tube containing the wiring terminals and connected with the annulus and having an inwardly extending portion exterior of the annulus and also having an upright portion arranged closely adjacent the upright portion of the pipe and an elastic sleeve embracing the upright portions 70
- 20 of the pipe and insulating tube and constituting a hand grasp. 75
- 25 5. An electrical water heater comprising an annulus having a receptacle, a heating unit arranged in said receptacle and having wiring terminal extending outside the receptacle, a pipe connected with the interior of the receptacle and having an inwardly extending portion and an upright portion, the latter adjacent to the center of the annulus, an insulating tube containing the wiring terminals and connected with the annulus and having an inwardly extending portion exterior of the annulus and also having an upright portion arranged closely adjacent the upright portion of the pipe and an elastic sleeve embracing the upright portions 80
- 30 of the pipe and insulating tube and constituting a hand grasp; the upright portion of the said pipe being equipped with a lateral bracket frictionally engaging and embracing said pipe portion, and the said bracket being equipped, in turn, with a thermometer carried at the upper side thereof. 85
- 35 6. An electrical water heater comprising an annulus having a receptacle, a heating unit arranged in said receptacle and having wiring terminal extending outside the receptacle, a pipe connected with the interior of the receptacle and having an inwardly extending portion and an upright portion, the latter adjacent to the center of the annulus, an insulating tube containing the wiring terminals and connected with the annulus and having an inwardly extending portion exterior of the annulus and also having an upright portion arranged closely adjacent the upright portion of the pipe and an elastic sleeve embracing the upright portions 90
- 40 of the pipe and insulating tube and constituting a hand grasp; the said pipe being equipped above the elastic embracing sleeve with a casing alongside the pipe, and the said wiring terminal including fuses disposed in said casing. 95

In testimony whereof I affix my signature.

HARRY C. WELCOMER.
